UNITED STATES PATENT OFFICE.

BERTRAND S. SUMMERS, OF PORT HURON, MICHIGAN.

ART OF MANUFACTURING FLAX FIBER FOR SPINNING.

Application filed December 4, 1920. Serial No. 428,187.

To all whom it may concern:

Be it known that I, BERTRAND S. SUMMERS, a citizen of the United States, residing at Port Huron, in the county of St. Clair and State of Michigan, have invented certain new and useful Improvements in the Art of Manufacturing Flax Fiber for Spinning, of which the following is a specification.

10 This invention relates to a new and improved apparatus for use in the manufacturing of flax fiber, and more specifically it relates to means adapted to carry away all refuse and dust from the apparatus used in the breaking and scutching of flax fiber.

In the present method of manufacturing flax fiber from flax straw for use in making linen or for other purposes a number of manual operators are required. The straw having been suitably wetted in streams or bogs or by spreading in the field, it is then hauled to the mill, and is mowed in the barn loft. From this loft, the straw is taken as needed for use in the mill. The straw is first passed through a mechanism known as a break, comprising one or more pairs of intermeshing corrugated rolls. The straw after going through the break is gathered in hanks or handfuls and passed to a scutcher who thrusts the hanks into the scutching wheel. The scutching wheel consists ordinarily of a drum provided with radial blades. When the drum is rotated rapidly, these blades beat out the wood and tow fiber from the flax straw, and the operator retains in his hand the long fiber or scutched line.

In the operation of the break and of the scutching wheel large volumes of dust and of small particles of wood and tow fiber are created. These large volumes of finely divided matter render the work unhealthy and uneconomical, and it is difficult to secure operators to work on these machines. This dust is also highly inflammable and greatly increases the fire risk. Attempts have heretofore been made to provide means for properly ventilating scutching machines, but they are of such form that it has generally been considered impossible to collect all of the dust arising from them. In general practice the refuse and tow are swept or scraped

from this scutching machine and work, and passed to the boiler or to the tow machine, as the case may be. This manner of operating results in work that is poorly done and expensive.

In my method of manufacture I utilize apparatus which combines in one machine the break and scutching drum. This machine is covered by Patent No. 1,306,032 granted June 10, 1919, and in itself forms no part of the present invention. Other machines of the same general nature may be used in connection with the apparatus of my invention.

It is an object of the present invention to provide new and improved means adapted to remove all dust and refuse from scutching machines, or other apparatus of similar types. It is also an object to provide means of this character adapted to remove this refuse without the necessity of handling it, and without permitting the dust to escape in the vicinity of the scutching machine. It is another object to provide apparatus capable of adjustment so that it may properly handle the work. It is an additional object to provide apparatus which is simple in construction, relatively inexpensive to manufacture and which may be readily installed in connection with existing scutching machines. Other and further objects will appear as the description proceeds.

My apparatus comprises broadly a system of ventilating hoods and ventilated conveyors, adapted to remove all refuse from the vicinity of the scutching machines as soon as it is created.

I have illustrated a preferred embodiment of my invention in the accompanying drawings,—in which—

Figure 1 is a plan view showing my apparatus assembled in connection with a plurality of scutching machines, certain portions being broken away;

Figure 2 is a side elevation of the apparatus shown in Figure 1; portions being broken away to better show the construction;

Figure 3 is a section taken on line 3—3, Figure 1;

Figure 4 is a perspective view showing the hoods for the scutching machines; and

Figure 5 is an enlarged view illustrating the construction of the conveyor members.

Referring now to the drawings, a number of scutching machines, 6, are located adjacent the conveyor box 7. The machines are provided with hoods 8, which are connected by pipes 9, to the exhaust header 10, from which the pipe 11 leads to the blower 12. The conveyor 13, passes over the pulleys 14, 15 and 16 and its lower run is enclosed in the conveyor casing or box 7. The box is provided with the upper portion 17, to which is connected the exhaust pipe 18, leading to the fan 19. This fan 19, is connected by the exhaust pipe 20, to the dust box 21, the dust box being provided with the plurality of flannel bags 22. These bags may be suspended from the wire 23, as shown, or supported in any desired manner.

The scutching machines are shown more in detail in Figure 3 and comprise the pair of opposed break rolls 24, 25, and the interacting scutching drums 26, 27. The break rolls are driven by a toothed connection with the arcuate surface of the rocker 30. This drive gives to the break rolls a rotary movement which is reversed in direction at each reversal of movement of the rocker arm. The hood 8, shown in detail in Figure 4, is fitted over the scutching machine, the inner portion of the hood being divided into three chambers. The curved partition 31, forms the rear chamber, which, as shown in Figure 3 encloses the scutching drums. The diagonal partition 32, forms the front of the intermediate chamber, this chamber being located above the break rolls 24, 25. The forward chamber is located forwardly of the working members of the machine.

The partition 32, intersects the enlarged lower portion of exhaust pipe, so that the pipe is adapted to draw from both the intermediate and the forward chambers. The damper 33, operated by the handle 34, is provided for the purpose of varying the proportion of the air taken from the intermediate and the forward chambers. The curved chute 35, extends from below the break rolls to the opening 36, in the side of the conveyor box and hood. This chute is entirely enclosed and has the upper member 37.

As best shown in Figure 3, the angular iron guideway 38, is suspended by the hangers 39, in the conveyor box, and serves to guide the working run of the conveyor. This conveyor comprises detachable sprocket links of the usual type. As shown in detail in Figure 5, the link 40, has pivoted thereto the conveyor fork 41. This fork is provided with the rear extension 42, and knee brace 43. The adjacent link 44, is provided with the roller 45. As shown in Figure 3, the roller 45, is carried upon the angle iron guideway 38, and the conveyor fork

has its upper portion and rear extension co-acting with the under side of the angle irons. This construction is such as to maintain the conveyor fork 41, in angular relation to the guideway. As shown in Figure 2, the left end of the conveyor has been elevated, but it may be constructed in any preferred manner to discharge refuse at any desired point.

In the use of my apparatus, the conveyor is continued in operation while the machines are being used, and the suction is also continuously created in the header 10, and the pipe 18. The operator of the scutching machine takes the hanks of flax and inserts the end of the hanks between the break rolls 24, 25. These rolls carry the flax straw between them so that it may be acted upon by the scutching drums 26, 27. Due, however, to the reversal of the direction of rotation of the break rolls, after the hanks of straw have been carried inward for the predetermined distance, the reversal of the break rolls draws the fiber outwardly. The operator has retained his grasp upon the hanks and reverses it to insert the unscutched end between the break rolls, and this end is operated upon by the break rolls, as before. During the breaking and scutching a large amount of dust and woody fragments are detached from the straw, the heavier particles fall down the chute 35, while the lighter particles are drawn off by the air suction through the intermediate and forward chambers of the hood. The fragments of woody matter beaten out by the scutching drum, fall down the chute 35, the material being carried by gravity and by air suction into the conveyor box 7. In this box the forks 41, sweep the wood and the tow fiber along the box and as shown in Figures 1 and 2, discharges it at the elevated end of the conveyor, which is preferably located in another room from the scutching machine so as to avoid the creation of dust adjacent to the machine. The lighter particles of matter in the conveyor box are carried through the perforated member 46, by the suction of the fan 19. This air drops a portion of its dust in the box 21, the air passing out through the porous bags 22, the bags, however, serving to retain any particles of dust still carried by the air. As shown in Figure 2, the conveyor forks 41, which are pivotally connected to the conveyor links, hang downward, as shown in 41^a, upon the idle travel of the conveyor and when they engage the upper partition 47, of the conveyor box at 41^b, they are swung upwardly and the rear extension 42 engages the cross bar 48, thus swinging the fork over, as shown at 41^c. As the forks are carried around the roller 16, they engage the angle iron guideway, as has been described.

By the use of apparatus constructed according to this invention all refuse and dust is automatically removed, without the necessity for any handling operation. The speed of operation of the conveyor, the draft created by the fan 12, and that created by the fan 19, may be varied to suit the amount of work. Similarly the proportion of draft allowed to the intermediate and forward hood chambers also may be varied so that the lift of the air may be sufficient to handle only the dust, or the smaller particles, as well, if desired. The forward chamber effectively prevents the passage of any of the dust outwardly toward the operator.

I claim:

1. Apparatus for treating flax straw comprising a plurality of individual scutching machines, a conveyor adapted to carry away the refuse from the machines, a box enclosing said conveyor, and means adapted to pass a dust carrying current of air through said box in the direction away from the scutching machines.

2. Apparatus for treating flax straw comprising scutching machines, a conveyor leading from said machines, a box enclosing said conveyor, the conveyor comprising an endless chain and carrier forks hingedly associated therewith, the forks being adapted to sweep the refuse from the scutching machines along the conveyor box, a flanged guideway extending adjacent the working travel of the conveyors, and members carried by the forks engaging opposite faces of the guideway flanges to retain the forks in angular relation to the chain.

3. Apparatus for treating flax straw comprising scutching machines, provided with breaking rolls and a scutching drum, a divided hood associated with the machine, one portion of the hood covering the scutching drum, a second portion covering the breaking rolls, separate passages leading from the two portions and means for creating currents of air in the passages.

4. Apparatus for treating flax straw comprising scutching machines, provided with breaking rolls and a scutching drum, a divided hood associated with the machine, one portion of the hood covering the scutching drum, a second portion covering the breaking rolls and a third portion opening in front of the breaking rolls and means adapted to create currents of air through the portions of the hoods.

5. Apparatus for treating flax straw comprising scutching machines, provided with breaking rolls and a scutching drum, a divided hood associated with the machine, one portion of the hood covering the scutching drum, a second portion covering the breaking rolls, a third portion opening in front of the breaking rolls, and means adapt-

ed to create currents of air through the portions of the hood, the second and third portions being connected to a common source of air current and means to vary the proportion of the common current affecting each portion of the hood.

6. Apparatus for treating flax straw comprising scutching machines, provided with breaking rolls and a scutching drum, a divided hood associated with the machine, one portion of the hood covering the scutching drum, a second portion covering the breaking rolls, a third portion opening in front of the breaking rolls, and means adapted to create currents of air through the portions of the hood, the portion covering the scutching drum being connected to a conveyor adapted to carry away refuse from the machine.

7. Apparatus for treating flax straw comprising scutching machines, provided with breaking rolls and scutching drums, a divided hood associated with the machine, one portion of the hood covering the breaking rolls, another portion opening in advance of the rolls, a common air exhaust pipe connected to the two portions and a damper in the pipe adapted to vary the exhaust from the two portions.

8. Apparatus for treating flax straw comprising scutching machines, provided with breaking rolls and a scutching drum, a divided hood associated with the machine, one portion of the hood covering the scutching drum, a second portion covering the breaking rolls, and the third portion opening in front of the breaking rolls and means adapted to create currents of air through the portions of the hood, the air being drawn downward from the first portion of the hood and upward from the last two portions of the hood.

9. Apparatus for treating flax straw comprising scutching machines, provided with breaking rolls and a scutching drum, a divided hood associated with the machine, one portion of the hood covering the scutching drum, a second portion covering the breaking roll, and the third portion opening in front of the breaking rolls and means adapted to create currents of air through the portions of the hood, the air being drawn downward from the first portion of the hood and upward from the last two portions of the hood, the air discharging into dust boxes adapted to receive the small refuse carried by the air, porous means permitting the exhaust of the air.

10. Apparatus for treating flax straw comprising scutching machines, provided with breaking rolls and a scutching drum, a divided hood associated with the machine, one portion of the hood covering the scutching drum, a second portion covering the breaking roll, and a third portion opening in

front of the breaking rolls and means adapted to create currents of air through the portions of the hood, the air being drawn downward from the first portion of the hood and upward from the last two portions of the hood, the air discharging into dust boxes adapted to receive the small refuse carried

by the air, porous fabric bags being associated with the dust boxes to permit exhaust of the air but to retain the refuse therein. 10

Signed at Chicago, Illinois, this 30th day of November, 1920.

BERTRAND S. SUMMERS.
